UNITED STATES PATENT OFFICE.

CHARLES M. NORRIS, OF DENVER, COLORADO.

INDICATOR.

Application filed August 20, 1926. Serial No. 130,491.

This invention relates to indicators, primarily designed for typewriters and its main object is to provide an indicator in the nature of a clip adapted to be secured to typewriting paper adjacent the bottom thereof to enable typists to ascertain that the bottom of the sheet is being reached, as the clip indicates the last line to be typed, with the result that uniform margins on typed sheets are assured.

This invention also consists in certain other features of construction and in the combination and arrangement of the several parts, to be hereinafter fully described, illustrated in the accompanying drawings, and specifically pointed out in the appended claim.

In describing my invention in detail, reference will be had to the accompanying drawings wherein like characters denote like or corresponding parts throughout the several views, and in which:

Figure 1 is a perspective view showing the platen of a typewriter and a piece of paper associated therewith, together with the application of the indicator which forms the subject matter of the present invention.

Figure 2 is a perspective view of the indicator per se.

Figure 3 is an edge elevation thereof. Referring to the drawings in detail the letter A indicates the platen of a typewriter and B a pieces of typewriter paper.

The indicator which is in the nature of a clip is slightly curved upon itself to conform to the curvature of the platen and includes a body 1 from which extends a centrally disposed finger 2. Arranged upon opposite sides of the centrally disposed finger are fingers 3 and 4 of equal length but are slightly shorter than the finger 2 so that the indicator can be expeditiously applied to the paper as will be readily apparent.

The indicator is formed of resilient metallic material, and is extremely thin and slightly curved as above set forth, so that it will readily pass about the platen as will be apparent. The free ends of the fingers are rounded so as to not injure any part of the typewriter or the paper with which the indicator is associated with.

From the above description and drawings, it will be obvious that the indicator is adapted to be applied to a sheet of typewriting paper adjacent the bottom thereof to indicate to the typist that the bottom of the paper is being reached during the typing operation, and the indicator may be colored red or other appropriate color so that it may be readily observed by the typist with the result that uniform margins will be provided on all sheets typed when the indicator is used therewith.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

A device of the character described comprising a body, fingers secured thereto and adapted to be associated with a sheet of typewriting paper, so as to indicate that the bottom of the paper is being reached while typewriting thereon, and said device being formed from resilient metallic material curved upon itself to follow the curvature of the platen of a typewriter and being colored so as to be readily observed by the typist.

In testimony whereof I affix my signature.

CHARLES M. NORRIS.
